United States Patent Office.

WILLIAM C. GOODWIN, OF HAMDEN, CONNECTICUT.

Design No. 4,368, dated September 27, 1870.

DESIGN FOR THE FIGURES OF A MECHANICAL TOY.

The Schedule referred to in these Letters Patent and making part of the same.

To all whom it may concern:

Be it known that I, WILLIAM C. GOODWIN, of Hamden, in the county of New Haven and State of Connecticut, have invented a new Design for Figure for Mechanical Toy; and I do hereby declare the following, when taken in connection with the accompanying drawing, to be a full, clear, and exact description of the same, and which said drawing constitutes part of this specification, and represents a front view.

This invention relates to a design for toys, such as are applied to heating apparatus to receive a power to operate them from the rising heat.

The design represents two children seated upon a plank, the plank placed across a log, and caused to

vibrate (being pivoted to the log) by power derived from a revolving wheel in connection with the said plank, so that the apparent effect is of the plank working over the log, in the manner of what is termed a "seesaw," as fully shown in the accompanying illustration.

I claim as my invention—

The design for figures for mechanical toys, as described and shown.

W. C. GOODWIN.
